UNITED STATES PATENT OFFICE.

CHARLES J. MALMBERG, OF THOMASTON, MICHIGAN.

OAR-LOCK.

No. 926,127.

Specification of Letters Patent.

Patented June 29, 1909.

Application filed May 9, 1908. Serial No. 431,860.

To all whom it may concern:

Be it known that I, CHARLES J. MALMBERG, a subject of the King of Sweden, residing at Thomaston, in the county of Gogebic and 5 State of Michigan, have invented certain new and useful Improvements in Oar-Locks, of which the following is a specification, reference being had therein to the accompanying drawings.

10 The invention relates to certain improvements in oar locks, and consists in the novel construction of a device of this character whereby the friction between the parts and the noise occasioned by rowing is reduced to 15 a minimum.

The invention further consists in the peculiar arrangement and combination of the various parts of the oar lock, and still further in certain details of construction that will be 20 hereinafter more fully set forth and pointed out in the claims.

In the drawings,—Figure 1 is a perspective view of my improved oar lock applied to a boat; Fig. 2 is a vertical central section 25 therethrough, some of the parts being shown in elevation; and Figs. 3, 4 and 5 are detached perspective views of certain parts of the oar lock forming the adjusting means for the anti-friction bearings.

30 In general, the oar lock consists primarily of a socket section, as A, adapted to be secured to the gunwale of a boat, an upright section B mounted upon the socket section for movement in a horizontal plane, and an 35 oar supporting section C carried by the upright section and arranged for movement in a vertical plane, these several movements between the parts permitting of forward and backward movement of the oar and the up- 40 and-down movement necessary in rowing.

The socket section referred to is preferably in the form of a bracket, provided with an arc-shaped section a adapted to be secured in any suitable manner to the outer side of 45 the boat gunwale, and a transverse section b extending over the gunwale top and provided centrally with the socket member b'.

The supporting section has a detachable engagement with the socket member, and is 50 adapted to be locked thereto during the operation of rowing by means hereinafter set forth. In construction, it comprises essentially a spindle D and a loosely fitting sleeve E, the movement of the sleeve upon the 55 spindle permitting the backward and forward movement of the oar.

To reduce the friction between the parts, I employ an antifriction bearing intermediate the sleeve and the spindle, and preferably one at each end of the sleeve as shown. The 60 antifriction bearings are preferably a series of spheres a', which at the lower end of the upright are adapted to rest upon a conical bearing F upon the lower end of the spindle, and are retained in place by means of lateral 65 and depending annular flanges c and d, as plainly shown in Fig. 2. At the upper end, a similar bearing is employed consisting of a series of balls or spheres d', laterally depending projecting annular flanges e f' respec- 70 tively, and a conical bearing J threaded upon an externally-threaded extension I upon the spindle end. A nut I' serves to lock the parts in place.

For the purpose of taking up play between 75 the parts I provide means for adjusting the bearings, and I have here shown the preferred construction of adjusting mechanism consisting of a cap plate K, centrally apertured as at a² to receive the threaded end of 80 the spindle, and slotted at a³ on opposite sides of the aperture, these slots permitting the extension through the cap when in place of lugs a⁴ upon the upper face of the bearing J. Over the cap described is arranged a ring L, 85 having a key b² engaging a keyway b³ formed longitudinally in the threaded stem I, the ring being thus held against relative rotary movement. Over the ring is arranged the thumb or wing nut I' previously referred to. 90 As thus constructed, the adjustment may be effected by first loosening the thumb nut and then turning the cap, which through the agency of the lugs a⁴ produces a correspond- 95 ing movement of the bearing J. After the proper adjustment is effected, the thumb nut is screwed down in place and the parts locked.

The oar-carrying section C is somewhat similar in construction to the upright just 100 described, comprising a sleeve M fixed to the upright sleeve E and disposed transversely in relation thereto, the two sleeves being pref- 105 erably cast in one piece, and a spindle O fitting within the sleeve and projecting there- beyond at its large end sufficiently to receive a strap member P which passes about the oar and forms a connection between the latter and the oar lock. At each end of the sleeve of the oar-supporting section I provide an 110 antifriction bearing and means for adjusting the bearings similar in construction to those

already described. The spindle O is continued beyond its conical bearing c^2 to form a receiving section c^3 , and the oar band or strap P is connected at its ends to this last-mentioned section by bolts d^2 which hold the strap firmly in place.

From the construction as set forth it will be obvious that the oar may be moved backwardly and forwardly in the operation of 10 rowing with much ease and with little if any noise, and the same is true of the vertical movement of the oar, which is permitted through the agency of the swivel connection between the supporting section and the 15 upright.

The upright and oar-supporting section are adapted to be carried by the oar, and are therefore removably mounted upon the 20 socket section. The preferable connection between the parts consists of an externally threaded shank G upon the spindle D, which is adapted to engage with an external thread H in the socket b^2 . To permit the upright to be inserted within the socket and quickly detached therefrom, the thread upon the shank 25 G is cut away on its opposite sides, as at e' , for substantially one-fourth of the circumference, and the thread H is similarly cut away or interrupted. By turning the spindle 30 shank so that the threaded portions will come opposite the grooves in the socket thread the insertion of the spindle may be effected, and then by partially rotating the spindle the threads engage and the parts are 35 interlocked. I preferably employ an operating lever for effecting the locking engagement, indicated by the reference-letter Q, this lever being apertured and internally 40 screw-threaded to permit of its being threaded upon the spindle shank as shown, and I further provide retaining means for the lever so that after the locking engagement between the parts has been effected there will be no chance of the spindle working loose and 45 becoming detached. The preferred form of retainer consists of a pin, as R, insertible through an aperture in the free end of the lever and a corresponding socket in the socket section, as plainly shown in Fig. 1.

50 What I claim as my invention is,—

1. In an oar lock, the combination with a socket section, of an upright detachably engaging therewith, the parts being fashioned to interlock upon partial relative horizontal 55 rotation, an oar supporting section carried by said upright, and means independent of said oar supporting section for holding the parts against relative movement after the interlocking engagement has been effected.

60 2. In an oar lock, the combination of a socket section and an upright detachably engaging the socket, the parts being fashioned to interlock upon partial relative horizontal 65 rotation, an oar supporting section carried by said upright, a lever independent

of said oar supporting section for rotating the upright, and a retaining member for the lever.

3. In an oar lock, the combination of a socket section internally screw threaded, and the thread being interrupted by oppositely disposed vertical grooves, of an upright section provided with a shank having a corresponding interrupted thread, an operating lever upon the upright, and a retainer for the 75 lever.

4. In an oar lock, the combination of a socket section and an upright detachably engaging the socket, the parts being fashioned to interlock upon partial relative rotation, an oar supporting section carried by 80 said upright and a lever for rotating said upright to effect the locking engagement.

5. In an oar lock, the combination with a socket section internally screw-threaded, 85 and the thread being interrupted by spaced vertical grooves, of an upright section provided with a shank having a corresponding interrupted thread, and a lever for rotating the upright to effect the locking engagement 90 between the parts.

6. In an oar lock, the combination with a socket section, of an upright detachably engaging the socket consisting of a spindle and a sleeve fitting the spindle for free rotary 95 movement, an oar supporting section comprising a sleeve similar to and arranged transversely of the upright sleeve and rigidly attached thereto, and a spindle mounted within the sleeve for free rotary movement, and a securing strap connected to the 100 spindle.

7. In an oar lock, the combination with a socket section, of an upright detachably engaging the socket comprising a spindle, and a sleeve fitting the spindle for free rotary movement, an oar-supporting section, comprising a sleeve arranged transversely of the upright sleeve and attached thereto, and a spindle mounted within said latter sleeve for 110 free rotary movement.

8. In an oar lock, the combination with a socket section, of a vertical spindle detachably engaging the same, a sleeve mounted upon the spindle for rotary movement, an 115 oar-supporting section comprising a sleeve arranged transversely of the first-mentioned sleeve and carried thereby, and a spindle mounted within the sleeve for rotary movement, and anti-friction bearings intermediate 120 the sleeve and spindles.

9. In an oar lock, the combination with a socket section, of a vertical spindle detachably engaging the same, a sleeve mounted upon the spindle for rotary movement, an 125 oar-supporting section comprising a sleeve arranged transversely of the first-mentioned sleeve and carried thereby, and a spindle mounted within the same for rotary movement, anti-friction bearings intermediate 130

the sleeves and spindles, and means for adjusting said bearings.

10. In an oar lock, the combination with a socket section, of a vertical spindle engaging the same, a sleeve mounted upon the spindle for rotary movement, an oar-supporting section comprising a sleeve arranged transversely of the first-mentioned sleeve and rigidly secured thereto, a spindle mounted within the sleeve for free rotary movement and a bearing for the oar carried by one end of said spindle, ball bearing races at the opposite ends of said sleeves, coöperating conical bearings at the opposite ends of said spindles, and means for adjusting said conical bearings in relation to the ball bearing races.

11. In an oar lock, the combination with

a socket section, of a vertical spindle engaging the same, a sleeve mounted upon the 20 spindle for rotary movement and having the ends thereof flared to form ball bearing races, coöperating conical bearings carried by the spindle, one of said conical bearings having a screw threaded engagement with the spindle, a cap plate apertured to engage said spindle and fitting over said conical bearing and its corresponding ball bearing race, and means for clamping said conical bearings in its different positions of adjustment. 25 30

In testimony whereof I affix my signature in presence of two witnesses.

CHAS. J. MALMBERG.
